Atty

UNITED STATES PATENT OFFICE.

WALTER B. TEMPLETON, OF CHICAGO, ILLINOIS.

JACK.

Application filed February 17, 1922. Serial No. 537,142.

To all whom it may concern:

Be it known that I, WALTER B. TEMPLETON, a citizen of the United States, residing at Chicago, in the county of Cook and State 5 of Illinois, have invented certain new and useful Improvements in Jacks, of which the following is a specification.

This invention relates to improvements in jacks, and has reference more particularly 10 to jacks of the general type disclosed in Letters Patent No. 1,325,963, granted to me December 23, 1919. Jacks of this type are commonly known in the trade as pole jacks, being employed principally for pulling and straightening telegraph and telephone poles, posts, and the like, and for straightening up 15 buildings and similar structures which have gotten out of plumb.

Fig. 2 of my aforesaid patent shows a jack 20 of this type as employed to straighten a telegraph or telephone pole from a canted position to a perpendicular position. As is well known, in many situations, notably on railway rights of way, poles of this character 25 are located along one edge of a ditch, and when the tilt or cant of the pole is toward or over the ditch, it is a matter of some difficulty to obtain a proper foundation or rest for the jack in effecting the pole straightening operation. If the jack is footed on the 30 opposite side of the ditch, it is too short to reach across and engage directly with the pole.

My present invention is the out-growth 35 and result of a study to remedy this situation, and to enable jacks of this type to be successfully used for straightening up poles and other objects in situations where the footing for the jack can be obtained only at 40 some distance from the base of the pole or other object to be straightened and the jack itself is too short to reach the pole direct. To this end, the principal distinguishing 45 characteristic of my present improvement resides in an attachment or accessory in the nature of a device by which the lifting bar of the jack is, in effect, extended lengthwise so as to enable it to reach the object to be 50 straightened across a considerable intervening space.

My present invention, its novel structural 55 features, mode of use, and advantages in situations of the kind referred to, will all be readily understood and appreciated by persons skilled in the art from the following

description, taken in connection with the accompanying drawing, wherein I have illustrated a practical and an improved embodiment of the invention in association with the pole jack of my aforesaid patent, although 60 it is to be understood that the features by which the reach of the jack is increased or enlarged are not limited to association and use with the particular jack shown and described. 65

Referring to the drawings—

Fig. 1 is a side elevation showing my improved jack employed in straightening an inclined or canted pole that overhangs a ditch, with the jack footed on the opposite 70 side of the ditch from the pole;

Fig. 2 is an enlarged side elevation of the upper end or head of the lifting bar of the jack, the cup shaped socket member mounted thereon, and lower end of the pole forming 75 the lifting bar extension seated in the socket member;

Figs. 3 and 4 are horizontal sections on the lines 3—3 and 4—4, respectively, of Fig. 2; and

Fig. 5 is a rear elevation of the head of the lifting bar of the jack.

Referring to the drawing, P represents a pole to be straightened, said pole being shown as leaning over a ditch or other depression 85 D in the ground, which makes it impossible to foot the jack within several feet of the base of the pole without erecting a suitable foundation therefor in the ditch or depression D. 90

J designates as an entirety the jack which, in its details, is herein shown as a copy of the pole jack forming the subject matter of my aforesaid patent, including a base or pedestal 10 to which the frame of the jack 95 is pivoted at 11, and a non-slipping rest or foundation piece 42 in the form of a section of an I-beam, together with a locking pawl 37 that co-operates with the catch 38 on the base 10 to lock the jack frame perpendicular 100 to the base when the jack is employed for straight lifting operations.

By reference to Fig. 5 it will be observed that the upper end or head 6 of the lifting bar of the jack is formed with a central 105 vertical slot 7 extending from front to rear of the head, and on its rear side with shallow recesses or concavities 8 on either side of the slot 7; the purpose of said slot and concavities, as set forth in my former pat- 110

ent, being to seat and grip the links of a lifting chain. In my present improvement, in the form herein shown and described, the said slot and concavities are utilized to support and securely hold a cup attachment 9, this latter having on one side a flat substantially vertical face 10 which bears against the front face of the head 6 of the lifting bar, and a radially extending stem 10 or shank 11 located centrally of its flat side 10 and fitting down into the vertical slot 7 of the head. The cup member 9 has at its upper end a horizontal flange 12 which rests on the top of the head 6, and on the opposite sides of the radial stem or shank 11 are formed a pair of lobes 13, best shown in Fig. 4, which fit into the recesses 8 and co-operate with the flat side 10 in securely holding the cup attachment rigid with the head 20 on which it is detachably mounted.

From the foregoing it will be seen that the cup attachment is mounted on the head by a simple downward movement on the latter, and may be withdrawn therefrom by a simple upward or lifting movement; but when engaged with the head it is rigidly supported by the latter against downward or tilting movement or lateral movement in either direction.

Seated in the cup 9 is the lower end of a pike pole 14 that, when in place, constitutes in effect a longitudinal extension of the lifting bar of the jack and is preferably provided with a sharp or pointed upper end 14' adapted to bite into the wood of the pole or other object to be straightened.

Fig. 1 illustrates the use of the device so clearly as to render verbal description useless. When using the device for straightening operations the angle of the jack frame to its base is, of course, constantly shifting, and therefore the locking pawl 37 is unlatched. The improvement readily enables the jack to be footed at a considerable distance from the base of the pole, for which purpose the pike pole 14 may be of any desired or suitable length, and thus avoids the necessity of preparing a special or artificial foundation or footing for the jack in close proximity to the base of the pole. Another advantage of the invention resides in the fact that by its use the jack can be made to operate at a more favorable angle to the pole or other object to be straightened, and is also enabled to engage with the latter at a higher point, at which less power is required to effect a straightening operation.

I have described in detail the particular structure illustrated in the accompanying drawing for the purpose of making clear the principle of my invention and disclosing one practical embodiment thereof, but it will be understood that the improvement is not limited to the particular pole jack herein disclosed, and that various changes and

modifications may be made without departing in any manner from the invention.

I claim—

1. The combination with a jack frame, and an endwise movable rack-bar slidably mounted therein, of a removable attachment member adapted to be fitted onto and supported by the upper end of said lifting bar and formed with a seat to support a pole extension of said lifting bar. 75

2. The combination with a jack having a pivotally jointed frame and base and an endwise movable lifting-bar, of a removable attachment member adapted to interfit with and be rigidly supported on the upper end of said lifting-bar, said attachment member being formed with a socket to seat the lower end of a pole extension of said lifting-bar. 80

3. The combination with a jack having an endwise movable lifting-bar, of an accessory for lengthening the reach of the jack, including a cup-shaped member adapted to seat the lower end of a pole extension of the lifting-bar, and a shank of said cup-shaped member removably interfitted with and supported by the upper end of said lifting-bar. 85

4. The combination with a jack having an endwise movable lifting-bar formed with a vertically slotted head, of an accessory for lengthening the reach of the jack, including a cup-shaped member adapted to seat the lower end of a pole extension of the lifting-bar, and a lateral shank of said cup-shaped member removably fitted within and behind the slot of said head. 90

5. The combination with a jack having an endwise movable lifting-bar, of a pole-engaging member removably mounted on and supported by the upper end of said lifting-bar, and a pole held by said pole-engaging member and constituting an extension of said lifting-bar to lengthen the reach of the jack. 105

6. The combination with a jack having an endwise movable lifting-bar, of a cup-shaped member removably mounted on and supported by the upper end of said lifting-bar, and a pole seated at its lower end in said cup-shaped member and constituting an extension of said lifting bar to lengthen the reach of the jack. 110

7. The combination with a jack having an endwise movable lifting-bar, of a cup-shaped member having a shank removably engaged with and supported by the upper end of said lifting-bar, and a pole seated at its lower end in said cup-shaped member and formed with a sharpened upper end, said pole constituting an extension of said lifting-bar to lengthen the reach of the jack. 115

8. As a new article of manufacture, a pole-jack accessory comprising a member adapted to be separably mounted on the head of the jack and formed with a socket 120

130

to seat the lower end of a pole extension of the lifting-bar of the jack.

9. As a new article of manufacture, a pole-jack accessory comprising a cup-shaped member formed with a shank or stem fitted to and adapted to be removably supported by the head of the jack.

10. As a new article of manufacture, a pole-jack accessory, comprising a member adapted to be removably mounted on the head of the jack and formed with a socket, and a pole extension of the lifting-bar of the jack removably fitted to said socket.

WALTER B. TEMPLETON.
